(57) **CLAIM**

The ornamental design for a triangle speaker with retractable members, as shown.

DESCRIPTION

FIG. 1 is a top perspective view of a triangle speaker with retractable members in an extended position.

FIG. 2 is side elevational view thereof. The opposite side elevational view is identical.

FIG. 3 is a front elevational view thereof.

FIG. 4 is a bottom plan view thereof.

FIG. 5 is a top plan view thereof.

FIG. 6 is a rear elevational view thereof.

FIG. 7 is a top perspective view of the triangle speaker with retractable members in a retracted position.

FIG. 8 is a side elevational view thereof. The opposite side elevational view is identical.

FIG. 9 is a front elevational view thereof.

FIG. 10 is a bottom plan view thereof.

FIG. 11 is a top plan view thereof; and,

FIG. 12 is a rear elevational view thereof.
